ACOUSTIC DEVICE

Application filed October 13, 1930. Serial No. 488,385.

This invention relates to an acoustic device and more particularly to the driving mechanism thereof.

An object of the invention is to change the magnitude of the force applied to the diaphragm from that of the force supplied by the driving mechanism. This has been accomplished by providing a connecting link arranged at an acute angle to the direction of the normal movement of the diaphragm, said connecting link including a flexible portion and an inflexible portion so that the magnitude of the force applied to the connecting link is different from the magnitude of the force applied to the diaphragm.

Another object of this invention is to provide a connecting link having a flexible portion and an inflexible portion. This has been accomplished by forming a portion of the link into a substantially U-shaped cross sectional area whereby the flexing of said formed portion is prevented.

Another object of this invention is to reduce the cost of the connecting driving mechanism without sacrificing its performance. This has been accomplished by providing a single flexible connecting link which is used instead of the conventional leverage mechanism used in changing the magnitude of the force in the conventional speakers. As is well known this leverage mechanism requires usually at least three movable parts and a support for the one that is fulcrumed. From this it can be readily seen that the number of parts has been reduced, without sacrificing efficiency of the device. This results in a saving in material, labor, time, parts and costs.

Further objects and advantages of the present invention will be apparent from the following description, reference being had to the accompanying drawings, wherein a preferred embodiment of one form of the present invention is clearly shown.

In the drawings:

Fig. 1 represents a cross section through an acoustic device.

Fig. 1a is a sectional view taken on the line 1a—1a of Fig. 1.

Fig. 2 is a sectional view, drawn to a larger scale and taken on the line 2—2 of Fig. 1.

Fig. 3 is a sectional view taken on the line 3—3 of Fig. 1, showing a cross-sectional view of the connecting link.

Fig. 4 discloses a fragmentary view of the connecting link, taken in the direction of the arrow 4 in Fig. 3.

Fig. 5 is a diagrammatic view of the connecting link in two positions the imaginary and the resulting or true movements of four important points being shown in approximately the right direction.

Referring to the drawings, a permanent magnet 12, secured to a frame or a radio chassis (not shown) in any suitable manner, supports a housing 14, which is fastened to the permanent magnet 12 and properly spaced therefrom by the studs 16, threaded at one end into the permanent magnet 12 as at 17. The free lengths of the studs 16 project through the interposed spacing members 18 while the locking nuts 20 are threaded upon the studs 16 and secured against loosening by the lock washers 22.

The housing 14 is provided with a flanged portion or rim 24 which serves as a support for a tone damping felt cone 26, which rests against the inner conical surface of the housing 14, a flared portion 28 of a reproducing cone or diaphragm 30 and a ring-like clamping member 32 of suitable form, which cooperates with the rim 24 to clamp the flared portion 28 of the diaphragm 30 and the stretched outer periphery of the felt cone 26. A plurality of screws 34, projecting through holes of the ring 32, the flared portion 28 of the diaphragm 30, the felt cone 26 and the rim 24 of the housing 14, receives locking nuts 36 which are secured by the lock washers 38, thus supplying the necessary pressure to produce enough friction between the supported parts 32, 30 and 26 and the supporting rim 24 to hold these members in a relatively rigid relation.

Referring particularly to Figs. 1 and 2, the driver or driving mechanism includes the permanent magnet 12 having the two poles 40 and 42 that have attached thereto in any suitable manner the pole pieces 44 and 46, respectively, which are made of magnetizable material and have secured thereto by screws 100.

52 or any other fastener brackets 48 and 50, respectively, of non-magnetizable material and suitable shape. The brackets 48 and 50 hold the speech coil supporting members 54 and 56 in the right position, each of which carries exactly half of the speech coils but of opposite polarity. An armature 58 is welded or otherwise fastened to a flexible cross bar 60 between the two speech coil supports 54 and 56 and projects through a central opening of these two supports 54 and 56 and between the innermost ends 45 and 47 of the pole pieces 44 and 46, respectively. Each end of the cross bar 60 is adjustably fastened to the brackets 48 and 50 respectively by screws 63 as clearly shown in Fig. 1a. The cross bar itself is actually twisted in its middle portion for allowing the armature 58 to oscillate between the said innermost ends 45 and 47 of the pole pieces 44 and 46, respectively, so as to actuate the diaphragm through the connecting link 64. The armature 58 is immersed in a magnetic field such that the force acting on one end of the armature is opposite in direction to the force acting upon the other end when the speech coil is energized. This causes the armature 58 to oscillate about the pivot in one plane only, but in either direction, depending upon the direction of flow of the exciting current in the coils. The different polarities on the ends of the armature 58 aid each other in oscillating the armature.

It must be clearly understood that the above described driver as well as the diaphragm with the housing could be of any other well known type, each of these members per se not forming part of my invention.

In order to have the proper acoustic reproduction it is sometimes necessary to change the relative magnitude of the force moving the diaphragm with respect to the magnitude of the force moving the armature, so as to produce the desired ratio of amplitudes between the high and low frequency audio tones or signals as is well known to those skilled in the art. Magnitude of force as used in the specification and claims refers to the distance through which the driving end of the armature is displaced or the distance through which the apex of the cone travels as the case may be.

The following description relates to a device that produces this desired change in the magnitude of the foregoing magnitude of forces that represents my invention.

Riveted to or otherwise secured to the armature 58 is the one flexible end 62 of a connecting link 64, the other flexible end 66 of the link 64 is secured to the center of a spider 68, cemented or otherwise secured to the diaphragm 30. A screw 70 passing through members 66, 67, spider 68 and the diaphragm 30 cooperates with a nut 72 to hold all of these parts in a relatively fixed position. The end 66 may be attached to the

diaphragm in any other suitable manner, however.

In order to prevent a sidewise movement of the cone a flexible member 76 having one end attached at 78 to the housing 14 and the other end attached to the cone may be provided.

Referring more particularly to Figs. 3 and 4, the connecting link 64 also provides an inflexible portion 74 by simply having a wider part of certain length bent into a U-shaped or semi-circular or any other shape which best insures inflexibility over the desired length. The two narrow flexible ends 62 and 66 of the link 64 may each be provided with a slot 76 to make these ends even more flexible.

Referring now to Fig. 5, the point E constitutes the pivot for the armature 58 while the two pole pieces 44 and 46 are partly shown in section. The flexible ends *a* and *b* as well as the inflexible portion *c* are shown in full lines in the one, and in dot-and-dash lines in the other position. The imaginary and the true or resulting movements of four points A, B, C and D will now be analyzed.

For the sake of analysis the arc through which the end of the armature moves will be considered a path. Then the horizontal component R_1 is only left, which is transmitted to the point B as K_1 , if the flexible end *a* were rigid or inflexible. Since this end *a* is flexible, an imaginary movement K_2 is resulting thereof, as, first, point B of the end *a* does not truly move horizontally the full amount of R_1 or K_1 , due to the flexing of the end *a*, and, second, the point B has to follow an evasive curve, also due to the flexing of the end *a*.

The result is a movement R_2 , that is transmitted to the point C as K_3 by the inflexible portion *c*. As, however, the point D of the flexible end *b* can move in horizontal direction only, the transmitted motion K_3 causes the point C to follow an evasive path or curve, which gives the component K_4 . The resulting movement of the point C is therefore R_3 , that is transmitted to the point D as K_5 by the imaginary inflexible end *b*. The end *b* however, being flexible, takes up a component K_6 , that itself is in reality a resultant of two components. The one counteracts the horizontal movement of the point D due to a certain resistance of the diaphragm against moving in horizontal direction to either side, the other is a lateral component, due to the flexing of the end *b*, started at C and taken up by the flexing end *b* itself. The resultant in the diagram, however, is R_4 in horizontal direction and constitutes the true horizontal movement of the diaphragm.

The diagram thus shows that the disposition of the described connecting member between the armature and the diaphragm produces the desired change in magnitude of the force applied to the link to that applied to the diaphragm.

It must be understood, however, that in the

four diagrams shown, all components that are affected by the flexibility of the two ends *a* and *b* can be drawn in an approximate direction only, as the influence of flexibility 5 does not readily allow a statical solution.

A different ratio of the change of the magnitude applied to the link to that supplied to the diaphragm can easily be made by simply changing the angle that the link forms with 10 the axis of the cone or by changing the flexibility of the two ends *a* and *b*, either by changing the width or length of the slots 66 or the thickness of the flexible ends, or by changing the length of the two ends *a* and *b*. 15 While the form of embodiment of the present invention as herein disclosed, constitutes a preferred form, it is to be understood that other forms might be adopted, all coming within the scope of the claims which follow. 20

What is claimed is as follows:

1. In an acoustic device, a movable diaphragm for reproducing sound, a driving mechanism for actuating said diaphragm 25 and a link mechanism connecting said driving mechanism and said diaphragm, said link mechanism comprising a flexible member arranged at an acute angle with respect to the direction of the normal movement of the diaphragm, said link being so arranged as to flex upon being actuated, thereby changing the magnitude of the force delivered with respect to the force applied.

2. An acoustic device comprising in combination, a frame, a diaphragm mounted in said frame, a driving mechanism and a flexible link for connecting the driving mechanism to the cone, said link being arranged at an acute angle with respect to the direction 40 of movement of said diaphragm so as to change the magnitude of the output force of the link with respect to the magnitude of the input force due to the flexing and to the angular arrangement of the link.

3. An acoustic device comprising in combination, a frame, a diaphragm mounted in said frame, a driving mechanism and a flexible link for connecting the driving mechanism to the diaphragm, said link delivering a 50 force of a different magnitude from that applied to it due to the flexing of the link.

4. An acoustic device for reproducing electrical impulses comprising in combination, a frame, a cone diaphragm mounted in said frame, a driving mechanism for actuating said diaphragm in response to electrical impulses, and a flexible connecting link for connecting the driving mechanism to the diaphragm, said link being arranged at an acute 60 angle with respect to the axis of said diaphragm so as to change the magnitude of the force delivered from that applied, said change resulting from a flexing of the link, and a flexible member for connecting the 65 apex of the cone to the frame whereby the

cone is actuated substantially along its axis.

5. A connecting link for connecting the driving mechanism of an acoustic device to its diaphragm, said link including a slotted flexible portion and an inflexible portion. 70

6. A mechanism for connecting the driving mechanism of an acoustic device to the diaphragm, said connecting mechanism including a flexible link that alters the magnitude of a force applied to the link with respect to the magnitude of the force delivered. 75

7. A connecting link for connecting the driving mechanism of an acoustic device to its diaphragm, said link including a flexible portion and an inflexible portion having a 80 U-shaped cross-sectional area.

8. A connecting link for connecting the driving mechanism of an acoustic device to its diaphragm, said link including an inflexible portion having a U-shaped cross-sec- 85 tional area and a flexible portion having a rectangular cross-sectional area.

9. An acoustic device for reproducing electrical impulses comprising in combination, a frame, a cone diaphragm mounted in said frame, a driving mechanism for actuating said diaphragm in response to electrical impulses, a connecting device including a rigid part arranged at an acute angle with respect to the axis of said diaphragm, said rigid part 90 having one end connected to the diaphragm and a part being flexibly arranged with respect to said rigid part for connecting the other end thereof to said driving mechanism, and a flexible member for connecting the apex 100 of the cone to the frame whereby the cone is actuated substantially along its axis.

10. An acoustic device for reproducing electrical impulses comprising in combination, a frame, a cone diaphragm mounted in said frame, a driving mechanism for actuating said diaphragm in response to electrical impulses, a connecting device including a rigid part arranged at an acute angle with respect to the axis of said diaphragm, said rigid part 105 having one end connected to said driving mechanism and a part being flexibly arranged with respect to said rigid part for connecting the other end thereof to said diaphragm, and a flexible member for connecting the apex of the cone to the frame whereby the cone is actuated substantially along its axis. 110

11. An acoustic device for reproducing electrical impulses comprising in combination, a frame, a cone diaphragm mounted in said frame a driving mechanism for actuating said diaphragm in response to electrical impulses, a connecting device including a rigid intermediate part arranged at an acute angle with respect to the axis of said diaphragm, a part being flexibly arranged with respect to said intermediate part for connecting the driving mechanism to one end of said intermediate link and a part for connecting 120 125 130

- the diaphragm to the other end of said intermediate part so as to deliver a different magnitude of force to the diaphragm through said intermediate part than shall be imparted from said driving mechanism to said intermediate part, and a flexible member for connecting the apex of the cone to the frame whereby the cone is actuated substantially along its axis.
10. 12. An acoustic device according to claim 9 in which the rigid part is of U-shaped cross sectional area and the part which connects the one end of said rigid part with the driving mechanism of rectangular cross-sectional shape.
15. 13. An acoustic device according to claim 10 in which the rigid part is of U-shaped cross sectional area and the part which connects the one end of said rigid part with the diaphragm is of rectangular cross-sectional shape.

In testimony whereof I hereto affix my signature.

JOHN D. SEABERT.
